[57] CLAIM

The ornamental design for wall mounted water purifier for home use, as shown and described.

DESCRIPTION

FIG. 1 is a top, front and left side perspective view of a wall mounted water purifier for home use showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof; and

FIG. 7 is a perspective view of an alternate position thereof on a reduced scale, the storage containers shown separately from the purifier for purposes of disclosure.
